UNITED STATES PATENT OFFICE.

JOHN L. OSGOOD, OF BUFFALO, NEW YORK.

CLOSURE FOR OILING-DUCTS.

1,157,250.

Specification of Letters Patent.

Patented Oct. 19, 1915.

Application filed March 3, 1914. Serial No. 822,243.

To all whom it may concern:

Be it known that I, JOHN L. Osgood, a citizen of the United States, residing at Buffalo, in the county of Erie and State of 5 New York, have invented a new and useful Improvement in Closures for Oiling-Ducts, of which the following is a specification.

This invention relates to that type of 10 valved covers or closures for oiling ducts which comprise a shell or casing, usually of small size, that is secured in the outer end of the oil hole and contains a spring-seated valve which normally closes an oil inlet orifice in the outer end of the shell and is 15 adapted to be pushed inwardly to open the orifice by the spout of the oil can when introducing the oil.

The object of the invention is to produce 20 a valved cover for oil ducts which is of an exceedingly simple and inexpensive construction, adapted to be made in small sizes, which affords an efficient closure for the oil hole, but in which the valve and its spring will not obstruct the free passage of the oil 25 into the duct when the valve is shoved inwardly off of its seat.

In the accompanying drawings: Figure 1 is a sectional elevation showing an oil hole closure embodying the invention in place 30 in an oil duct. Fig. 2 is an enlarged sectional elevation of the closure removed. Fig. 3 is an enlarged sectional elevation showing the parts of the closure before they are assembled. Fig. 4 is an enlarged sectional plan of the closure. Fig. 5 is an enlarged sectional elevation thereof showing the valve unseated.

A represents the shell or casing of the closure which is seated in an enlarged or 40 counterbored outer end portion of an oil duct, indicated at *a*, and has an outer or upper end provided with an inlet orifice *a'* for the introduction of the oil and an open inner or lower end. The inlet orifice *a'* is 45 normally closed by a valve B, preferably consisting of a small steel ball, which is movably confined in the shell and is held against a conical seat *b* surrounding the inlet orifice *a'* by a coil spring C which bears 50 at its inner end against an internal flange or part D at the inner end of the shell. This flange is preferably formed by spinning inwardly the integral end portion of the shell.

The walls of the shell are provided with 55 one or more, preferably two, longitudinal

slots E. These slots preferably extend from near the outer end of the shell to the extreme inner end thereof, intersecting the spring bearing flange D and being open at their inner ends. The slots form passages 60 independent of the open inner end of the shell through which the oil can discharge from the shell into the oil duct *a*, and the oil can escape from the shell both through its open inner end and through the slots E, or 65 through the slots alone should the open end of the shell be obstructed. If, therefore, in the use of the device the valve should be shoved inwardly far enough to completely 70 collapse the spring and cause the opening 70 at the inner end of the shell to be obstructed by the ball and the collapsed spring, as indicated in Fig. 5, the escape of the oil will not be cut off, since the oil can flow down around the ball and spring and out through the 75 slots E which extend above the spring and the middle of the ball when the ball is in its lowest position. It is therefore impossible 80 to obstruct the discharge of the oil from the shell by shoving the ball inwardly too 80 far, even in the smallest sizes of closures, and this construction permits the use of 85 solid ball valves, which are more satisfactory and less expensive to make than valves of special construction. The slots E also 85 enable the walls of the shell to spring slightly and retain the closure securely in place by their pressure against the walls of the cavity in which the closure is seated.

By the described construction a practical 90 and efficient closure is produced which is composed of only three parts, the shell, the ball and the spring, which are of the simplest conceivable construction and can be manufactured at the minimum expense. The 95 shell can be made from solid cylindrical stock simply by boring the cavity with an ordinary drill, the conical point of which at the same time forms the beveled or conical seat *b* for the ball valve.

I claim as my invention.

1. In a closure for oil ducts, the combination of a single-piece integral shell which is adapted to be located in a retaining cavity and has an open inner end and an oil inlet orifice in its outer end, and a spring-seated valve in said shell for closing said inlet orifice, said shell having laterally yielding side walls at its inner end which contract when the shell is forced into said cavity and which 110

grip the walls of the cavity to frictionally hold said shell in said cavity.

2. In a closure for oil ducts, the combination of a shell which is adapted to be located in a retaining cavity and has an open inner end and an oil inlet orifice in its outer end, and a spring-seated valve in said shell for closing said inlet orifice, the inner end of said shell being bifurcated, whereby 10 the bifurcated portions of the shell are pressed toward each other when the shell is forced into said cavity, and frictionally grip the side walls of the cavity.

3. In a closure for oil ducts, the combination of a shell which is adapted to be located in a retaining cavity and has an open inner end and an oil inlet orifice in its outer end, and a spring-seated valve in said shell for closing said inlet orifice, said shell having a slot in its side wall extending to the inner end of the shell through which the oil can discharge from the shell and which permits the inner end of the shell to be contracted when placed into said cavity and to yield-

ingly grip the walls of the cavity to hold the 25 shell in place therein.

4. In a closure for oil ducts, the combination of a single-piece integral shell having at one end an inlet orifice surrounded by a valve seat and at the other end a discharge 30 opening surrounded by an inturned flange forming a bearing for a spring, a ball valve in the shell adapted to engage said seat for closing the inlet orifice, and a spring for yieldingly seating said valve, said spring 35 bearing at one end against said ball valve and at its other end on said inturned flange, said shell having a longitudinal slot in its side wall open at said other end of the shell through which the oil can discharge from 40 said shell.

Witness my hand, this 28th day of February, 1914.

JOHN L. OSGOOD.
